UNITED STATES PATENT OFFICE.

FRANK P. EDDY, OF EUNICE, MISSOURI.

VEHICLE-BRAKE.

SPECIFICATION forming part of Letters Patent No. 630,871, dated August 15, 1899.

Application filed November 12, 1898. Serial No. 696,264. (No model.)

To all whom it may concern:

Be it known that I, FRANK P. EDDY, a citizen of the United States, residing at Eunice, in the county of Texas and State of Missouri, 5 have invented a new and useful Vehicle-Brake, of which the following is a specification.

This invention relates generally to vehicle-brakes, and more particularly to an automatic brake which operates to check or stop 10 the vehicle the moment the draft thereon is slackened or stopped.

The object of the invention is to provide an exceedingly cheap and simple construction of 15 automatic brake which can be applied to any of the vehicles now in use without disturbing the running-gear proper.

Another object is to provide means for regulating the tension of the brake-operating mechanism whereby the brake-shoe can be 20 applied quickly or gradually, according to the weight of the load being carried.

With these objects in view the invention consists, essentially, of a brake-beam suspended beneath the body of the vehicle and carrying brake-shoes at its ends adapted to 25 contact with the rear wheel, spring-operated means attached to the rear axle and connected with the brake-beam to draw the shoes into such contact, and chains and levers arranged 30 in advance of the brake-beam and connected with a draft-evener or doubletree, whereby the brake beam and shoes are held released so long as draft is applied to the evener or doubletree.

35 The invention consists also in certain details of construction and novelties of combination, all of which will be fully described hereinafter and pointed out in the claims.

In the drawings forming part of this specification, Figure 1 is a top plan view of the running-gear and brake mechanism, and Fig. 2 is a detail vertical section of the vehicle and gear.

40 In carrying out my invention I employ the ordinary form of running-gear comprising the front axle and bolster A, the rear axle and bolster B, connecting reach or pole C, and the front hounds A' and the rear hounds B'.

The brake-beam D is suspended from the 45 body of the vehicle by means of suitable rings D' and carries brake-shoes D² at its opposite ends, adapted to contact with the rear wheels.

Chains or rods E are attached to the brake-beam D near each end, said chains or rods E extending rearwardly and connected to a 55 follower-plate F, arranged upon the bolt G, which passes through the rear axle and has a spiral spring H arranged thereon between the head of the bolt and the follower-plate F, the purpose of said spring being to normally 60 hold the brake-shoes against the wheel through the medium of the rods or chains E. The tension of the spring H upon the follower-plate F is regulated through the medium of an end nut I, mounted upon the end 65 of the bolt upon the rear side of the rear axle B, and by tightening or loosening the said nut the bolt is adjusted in the axle, and consequently the tension of the spring increases or decreases, as desired.

70 Chains or rods K are attached to the forward side of the brake-beam opposite the rods or chains E and extend forwardly, connecting at their forward end to the levers K', pivotally connected to each other and to the 75 reach C, directly to the rear of the front hounds. The rods or chains K are connected to the levers intermediate their ends, and chains L are attached to the outer ends of the levers and extend forwardly and connect with the doubletree or evener upon opposite sides 80 of the pivot, and in order to insure uniform operation of the various parts I arrange cross-chains M, which extend from the chains L from a point about midway the length of said 85 chains and connect with the end of the oppositely-arranged lever K', and by means of this construction both levers will be operated whether the draft is equal or unequal, as it will be seen that both levers are connected 90 directly to both sides of the doubletree or evener. The tongue or draft-pole is slotted longitudinally at N for a short distance where the pivotal bolt passes in order to permit a limited movement of the said tongue without 95 interfering with the brake mechanism. In operation it will be understood that the spring will normally hold the brake-shoes in contact with the rear wheels; but the moment the draft is exerted upon the doubletree or evener 100 the forward chains operate upon the levers K, drawing their outer ends forwardly, which action causes the chains K to be drawn forwardly and pulls the break-beam forward and

releases the brake. The moment, however, the draft ceases or slackens the spring begins to act and draw the brake-shoe against the rear wheels, and by regulating the tension of the spring the brakes can be made to act quickly or gradually, according to the weight of the load to be carried. When it is desired to back the wagon without applying the brakes, the draft-animals are turned to one side, throwing the entire draft upon one side of the evener, and this operation serves to hold the levers K' forwardly and the brake released.

Another advantage of the invention is that when starting the evener has a limited movement on account of the slot in the pole or tongue, and the draft is first applied to the spring, so that the strain upon the animals in starting is considerably decreased.

Having thus fully described my invention, what I claim as new, and desire to secure by Letters Patent of the United States, is--

1. In a vehicle-brake, the combination with the draft-evener, of the chains extending rearwardly therefrom, the levers to which said chains are connected, said levers being also connected with the brake-beam, and the cross-chain extending from the draft-chains to the ends of the oppositely-arranged levers, substantially as shown and described. 25

2. In a vehicle-brake, the combination with the brake-beam, of the operating rods or chains, the follower-plate, to which said rods or chains are attached, the bolt upon which said follower-plate slides, the coil-spring surrounding the bolt and bearing upon the plate, and the hand-nut for regulating the tension of the spring, and the draft-chains and lever for releasing the brake-beam, substantially as shown and described. 30

FRANK P. EDDY.
